CLAIM

The ornamental design for a wall-mounted soap dish, as shown and described.

DESCRIPTION

FIG. 1 is a top, front, and right side perspective view of a wall-mounted soap dish showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side being a mirror image of that shown;

FIG. 7 is a vertical cross-sectional view thereof, taken along line 7—7 of FIG. 4; and,

FIG. 8 is a vertical cross-sectional view thereof, taken along line 8—8 of FIG. 4.

FIG. 1

FIG. 2

FIG. 3

FIG. 6

FIG. 7

FIG. 8
